REAMER CUTTER MOUNTING

John H. Howard, Huntington Park, and Alfred C. Catland, Alhambra, Calif.; said Catland assignor to Globe Oil Tools Company, a corporation of California

Application May 13, 1936, Serial No. 79,491

8 Claims. (Cl. 255—73)

This invention relates to well reamers and relates more particularly to mountings for the roller cutters of well reamers. A general object of this invention is to provide improved practical and particularly efficient anti-friction mountings for roller reamer cutters.

Another object of this invention is to provide a simple, inexpensive, anti-friction bearing means for dependably rotatably supporting the roller cutter of a well reamer.

Another object of this invention is to provide an anti-friction roller bearing means for supporting a roller cutter that is very easy and convenient to assemble.

Another object of this invention is to provide a roller bearing mounting for the roller cutter of a well tool that embodies means for retaining the rollers in position prior to and during the insertion of the cutter supporting pin through the cutter.

It is a further object of this invention to provide an improved anti-friction ball bearing means for rotatably supporting the roller cutter of a well tool that is easy and convenient to assemble and that provides for the proper uniform distribution of the load or active forces throughout the length of the cutter.

The various objects and features of our invention will be fully understood from the following detailed description of typical preferred forms and applications of our invention, throughout which description reference is made to the accompanying drawings, in which:

Fig. 1 is a side elevation of a well reamer embodying one form of the present invention. Figs. 2, 3 and 4 are enlarged transverse detailed sectional views taken as indicated by lines 2—2, 3—3 and 4—4, respectively, on Fig. 1. Fig. 5 is an enlarged longitudinal fragmentary detailed sectional view taken substantially as indicated by line 5—5 on Fig. 1. Fig. 6 is an enlarged fragmentary vertical detailed sectional view illustrating the cooperation of a roller with the spacer. Fig. 7 is an enlarged fragmentary vertical detailed sectional view illustrating the cooperation of a roller with a washer. Fig. 8 is a view similar to Fig. 5 illustrating an alternative form of bearing means and Fig. 9 is a fragmentary vertical detailed sectional view of a reamer illustrating a form of ball bearing cutter mounting provided by the invention.

The improved bearing means of the present invention is adapted to be employed in well reamers and well tools varying considerably in character. In the following detailed description we

will disclose the invention embodied in a well reamer of the general character set forth in Patent No. 2,035,888, issued to J. H. Howard on March 31, 1935. It is to be understood that the invention is not to be construed as limited or restricted to the specific constructions or applications about to be described.

The well reamer illustrated in the drawings comprises a shank or body 10 to be interposed in a well drilling string. The body 10 is an elongate member provided at its ends with means for connecting it in the string. In the case illustrated a tapered threaded pin 11 is provided at the upper end of the body 10 and a tapered threaded socket 12 is provided in the lower end of the body. A central longitudinal fluid passage 13 extends through the body 10 from one end to the other to conduct the circulation fluid. The intermediate portion 14 of the body 10 is shaped and proportioned to carry the reaming roller cutters 15. The particular reamer illustrated has three circumferentially spaced cutters 15 and the body portion 14 is substantially triangular in horizontal cross section. Recesses 16 are provided in the apex parts of the body portion 14. The recesses 16 extend vertically or longitudinally and have flat upper and lower end walls. The inner walls of the recesses 16 are concave and curved. The recesses 16 may be alike in size and shape.

The reamer cutters 15 are substantially cylindrical roller cutters. The cutters 15 are provided with suitable teeth or cutting parts 17. Each cutter 15 has a central longitudinal opening 18 extending through it from one end to the other. The several cutters 15 are illustrated as being alike. However, the cutters may have cutting parts or teeth 17 of various characters. The lower portions of the cutters 15 are preferably tapered downwardly and inwardly.

The form of cutter mounting means of the present invention illustrated in Figs. 1 to 7, inclusive, of the drawings, includes, generally, a pin 20 extending through each body recess 16, series of rollers 21 in each cutter 15 for rotatably supporting the cutter on the pin 20, spacers 22 between the series of rollers 21, and washers 23 at the ends of the cutters 15. As the means for rotatably supporting the cutters 15 may be identical we will proceed with a detailed description of the means for rotatably supporting one cutter 15, it being understood that such description is equally applicable to the mountings of the several cutters.

The pin 20 of the cutter mounting means ex-

- tends longitudinally through a body recess 16 to carry a cutter 15 and its bearing elements. The pin 20 is an elongate cylindrical part whose opposite end portions are carried by the body 10.
- 5 5 An opening 24 in the body portion 14 communicates with one end of the recess 16 and a similar opening 25 in the body portion 14 communicates with the other end of the recess. The pin 20 has one end portion carried in the opening 24 10 and has its other end portion carried in the opening 25. A stop 26 is provided in the opening 25 to limit the longitudinal movement of the pin 20. The stop 26 may be welded or otherwise secured in the opening 25.
- 15 15 Means is provided for removably locking the pin 20 against movement. A transverse opening 27 is provided in the body portion 14 and partially intersects the opening 24. A notch 28 is provided in the pin 20 to register with the opening 27. A lock pin 29 is arranged in the opening 27 to cooperate with the notch 28. The pin 29 cooperating with the notch 28 dependably locks the pin 20 against rotation and longitudinal movement. A set screw 30 is threaded in the 25 outer portion of the opening 27 to hold the pin 29 against a shoulder 31 on the wall of the opening 27. A cotter key 32 holds the screw 30 against unthreading. A reduced opening 32^a communicates with the inner end of the opening 30 30 27 to permit the pin 29 to be knocked out when the screw 30 is removed. The cutter supporting pin 20 extends through the openings 18 of the cutter 15 with substantial clearance to leave an annular space for receiving the bearing rollers 21 and the spacer 22.
- 35 35 The series of rollers 21 are provided in the opening 18 of the cutter 15 to cooperate with the wall of the opening and the pin 20 and thus rotatably support the cutter 15 on the pin. The 40 rollers 21 are elongate cylindrical hardened steel members of the proper length and diameter. In the preferred construction illustrated, there are two series of rollers 21 surrounding the pin 20 and spaced apart longitudinally of the pin to be 45 within the opposite end portions of the cutter 15. In accordance with the invention the opposite ends of the anti-friction rollers 21 are bevelled or tapered having inclined surfaces 34. The rollers 21 may have relatively small flat faces 35 at 50 their extremities. In the form of the invention being described the rollers 21 are positioned so that their outer ends are at the ends of the cutter 15.
- 55 55 The spacer 22 is provided to space apart the two series of rollers 21. The spacer 22 is in the nature of a tube or sleeve surrounding the pin 20 and fitting the cutter opening 18 with suitable clearance. The opposite ends of the spacer 22 are shaped for cooperation with the 60 rollers 21. A lip 36 is provided on each end of the spacer 22. The lips 36 are continuous or annular. The inner sides or surfaces of the lips 36 are continuations of the internal wall of the spacer 22. The outer sides or surfaces 37 of the 65 lips 36 are tapered or inclined to cooperate with the tapered surfaces 34 of the rollers 21. The cooperation of the surfaces 34 and 37 facilitates the easy assembly of the rollers 21 in the cutter 15 as will be subsequently described. Flat normal end surfaces 38 are provided on the spacer 22 at the bases of the lips 36. The end faces 35 of the rollers 21 are adapted to cooperate with these 70 surfaces 38. As the rollers 21 of the two series 75 are of the same length the spacer 22 just de-

scribed is located intermediate the ends of the cutter 15.

The washers 23 are provided to space the ends of the cutter 15 and the outer ends of the rollers 22 from the end walls of the recess 16. The 5 washers 23 surround the pin 20 at the opposite ends of the cutter 15. In the preferred construction the washers 23 are square or flat sided and are received in correspondingly shaped notches 39 occurring in the end walls of the recess 16. The 10 washers 23 thus received in the flat walled notches 39 are held against rotation. In accordance with the invention a lip 40 is provided on each washer 23 to cooperate with the inclined end 15 surfaces 34 of the rollers 21. The lips 40 are annular and surround the pin 20. The lips 40 each have a tapered or inclined outer surface 41 for cooperating with the surfaces 34 of the rollers 21 to aid in facilitating the easy assembling of 20 the rollers. The major exposed surfaces of the washers 23 are flat for cooperation with the flat 25 ends of the cutter 15 and the flat end surfaces 35 of the rollers 21.

In assembling the cutter 15 and the cutter 25 mounting just described the rollers 21 and the spacer 22 are arranged in their proper positions in the opening 18 of the cutter. The washers 23 are then placed against the opposite ends of the cutter 15. With the parts in these positions the lips 36 of the spacer 22 cooperate with the surfaces 34 of the rollers 21 to hold the adjacent 30 ends of the rollers 21 against inward displacement. In a like manner the lips 40 of the washers 23 cooperate with the surfaces 34 of the rollers 21 to hold the outer ends of the rollers against 35 inward displacement. Thus the lips 36 and 40 engage the ends of the rollers 21 to retain the rollers in position. The cutter 15 containing the rollers 21 and the spacer 22 is then inserted in the recess 16, together with the washers 23 at its 40 opposite ends. The washers 23 are, of course, entered in their respective notches 39. The pin 20 is passed inwardly through the opening 24 and through the series of rollers 21 and the spacer 22 to have its end portion received in the opening 25. 45 As above described the lips 36 and 40 retain the rollers 21 in place and thus facilitate the easy insertion of the pin 20. Following insertion of the pin 20 the pin 29 is arranged in the opening 27 and is secured in place by the screw 30. 50

The cutter mounting means illustrated in Figs. 1 to 7, inclusive, of the drawings is particularly simple and effective. The spacer 22 and the washers 23 are simple parts and cooperate with the rollers 21 as just described to greatly facilitate the assembling of the tool. The rollers 21 operate to support the cutters 15 with a minimum of friction. The parts of the cutter mountings as well as the cutters 15 may be easily removed 55 for replacement.

Fig. 8 of the drawings illustrates a form of the invention similar to that just described. The cutter supporting pin 20 and the spacer 22 may be identical with the pin and spacer of the previously described form of the invention. The anti-friction rollers 21^a are of the same shape as the rollers 21 but are slightly shorter than the rollers 21 to have their outer ends some distance inwardly from the ends of the cutter 15. The rollers 21 have tapered or inclined end surfaces 34^a. In the 65 embodiment of the invention illustrated in Fig. 8 of the drawings a spacer ring 45 is arranged in each end portion of the cutter opening 18 to space the ends of the rollers 21^a from the washer 23^a. The rings 45 are provided with annular lips 40^a 70

75

similar in shape and operation to the lips 40. The washers 23^a are identical with the washers 23 except that they are devoid of the lips 40. The lips 36 and 40^a cooperate with the inclined end surfaces 34^a of the rollers 21^a to retain the rollers in position during the assembling of the cutter on the tool. Except for the details just described the construction illustrated in Fig. 8 is identical with that illustrated in Figs. 5 to 7 inclusive, and 10 has the same mode of operation.

Fig. 9 of the drawings illustrates another form of roller cutter mounting means. The construction illustrated in Fig. 9 of the drawings includes, generally, a pin 20^a extending through the body recess 16, a bearing sleeve 50 surrounding the pin 20^a within the opening 18 of the cutter 15, steel balls 51 carried by the sleeve 50 and washers 52 spacing the ends of the cutter 15 and the sleeve 50 from the end walls of the recess 16. 15 The pin 20^a may be identical with the pin 20 and extends through the opening 18 of the cutter 15 with clearance, leaving an annular space to receive the bearing sleeve 50. The bearing sleeve 50 is an elongate tubular element. The sleeve 50 surrounds the pin 20^a with suitable clearance and has suitable clearance with the wall of the opening 18. The opposite ends 53 of the sleeve 50 may be flat and normal and in the same planes as the ends of the cutters 15. In accordance with the invention a multiplicity of openings 54 is provided in the sleeve 50 to receive the balls 51. The openings 54 are spaced circumferentially and longitudinally to provide for the proper distribution of the load on the cutter 15 and pin 20^a. In the preferred construction illustrated the openings 54 are arranged in a spiralled row or series. The openings 54 are shaped to facilitate the retention of the balls 51 in the sleeve 50. The openings 54 are tapered having outwardly flared or divergent walls.

The anti-friction balls 51 are provided in the openings 18 to support the cutter 15 for rotation with a minimum of friction. The balls 51 are steel balls of sufficient diameter to properly cooperate with the pin 20^a and the wall of the cutter opening 18. The washers 52 may be flat surfaced washers for cooperating with the ends of the cutter 15 and sleeve 50. The washers 52 are preferably flat sided to fit the notches 39 whereby they are held against rotation. The openings 54 being in a spiralled series support the balls 51 so that they do not track in their contact with the pin 20^a and the cutter 15.

In assembling the construction illustrated in Fig. 9 of the drawings the sleeve 50 is introduced or started in the opening 18 of the cutter 15. When the sleeve 50 is in a position where its lowermost opening 54 is adjacent the end of the cutter 15 a ball 51 is inserted in the said opening 15 and the sleeve is moved downwardly so that the ball is entered in the opening 18. The tapered wall of the said lowermost opening 54 prevents the ball from falling inwardly in the sleeve while the wall of the cutter opening 18 of course prevents the ball from falling outwardly. A ball 51 is then inserted in the next opening 54 and the sleeve 50 again moved downwardly to bring the ball within the opening 18 of the cutter. This procedure is repeated until a ball 51 has been arranged in each of the openings 54. The sleeve 50 is then entirely or substantially entirely within the cutter 15. The washers 52 are then arranged in the notches 39 and the cutter 15 carrying the sleeve 50 is inserted in the recess 16. The pin 20^a 75 is then arranged through the opening 24 and the

sleeve 50 to have its inner end portion received in the opening 25. The pin 20^a may be locked in place with the pin 29 in the same manner as the pin 20.

The form of the invention illustrated in Fig. 9 of the drawings dependably supports the cutter 15 for rotation with a minimum of friction. The balls 51 are retained in proper spaced relation in the openings 54 to assure the proper distribution of the forces. The tapered openings 54 of the sleeve 50 retain the balls 51 to facilitate the easy assembling of the pin 20^a through the cutter. It is to be noted that the several forms of the invention provide for the retention of the anti-friction elements in their operative positions during the 15 assembling of the cutter on the tool body 10 to greatly facilitate the assembling of the tool.

Having described only typical preferred forms and applications of our invention, we do not wish to be limited or restricted to the specific details 20 herein set forth, but wish to reserve to ourselves any variations or modifications that may appear to those skilled in the art or fall within the scope of the following claims.

Having described our invention, we claim: 25

1. In a well tool, a body, a roller cutter having an opening, a pin carried by the body and extending through the opening, series of anti-friction rollers in the opening surrounding the pin, said rollers having reduced ends, a spacer between said 30 series of rollers, and lips on the spacer cooperating with the adjacent reduced ends of the rollers.

2. In a well tool, a body, a roller cutter having an opening, a pin carried by the body and extending through the opening, series of anti-friction 35 rollers in the opening surrounding the pin, said rollers having reduced end parts, a spacer in the cutter between the series of the rollers, lips on the spacer cooperating with the adjacent end parts of the rollers, washers on the pin spacing the ends 40 of the cutters from the body, and lips on the washers cooperating with the adjacent end parts of the rollers.

3. In a well tool, a body, a roller cutter having an opening, a pin carried by the body and extending through the opening, series of anti-friction 45 rollers in the opening surrounding the pin, said rollers having reduced end portions, washers on the pins spacing the ends of the cutter from the body, and lips on the washers cooperating with 50 adjacent end portions of the rollers.

4. A construction for rotatably supporting a roller cutter on a well tool body including, a pin to be carried by the body to extend through the cutter, series of anti-friction rollers surrounding 55 the pin to rotatably support the cutter thereon, the rollers having tapered end surfaces, a spacer in the cutter between the series of rollers, and annular lips on the spacer having inclined surfaces cooperating with the adjacent tapered end 60 surfaces of the rollers.

5. A construction for rotatably supporting a roller cutter on a well tool body including, a pin to be carried by the body to extend through the cutter, series of anti-friction rollers surrounding 65 the pin to rotatably support the cutter thereon, the rollers having tapered end surfaces, washers spacing the ends of the cutter from the body, annular lips on the washers having inclined surfaces cooperating with the adjacent tapered end 70 surfaces of the rollers, a spacer in the cutter between the series of rollers, and annular lips on the spacer having inclined surfaces cooperating with the adjacent tapered end surfaces of the rollers.

6. A construction for rotatably supporting a roller cutter on a well tool body including, a pin to be carried by the body to extend through the cutter, series of anti-friction rollers surrounding the pin to rotatably support the cutter thereon, the rollers having tapered end surfaces, washers on the pin at the ends of the cutter, rings on the pin in the end portions of the cutters spacing the rollers from the washer, and annular ridges on the rings cooperating with the adjacent tapered end surfaces of the rollers.
7. A construction for rotatably supporting a roller cutter on a well tool body including, a pin to be carried by the body to extend through the cutter, series of anti-friction rollers surrounding the pin to rotatably support the cutter thereon, the rollers having tapered end surfaces, a tubular spacer on the pin spacing the series of rollers, annular ridges on the spacer cooperating with the

adjacent tapered end surfaces of the rollers, washers on the pin at the ends of the cutter, rings on the pin in the end portions of the cutter spacing the rollers from the washer, and annular ridges on the rings cooperating with the adjacent 5 tapered end surfaces of the rollers.

8. A construction for rotatably supporting a roller cutter on a well tool body including, a pin to be carried by the body to extend through the cutter, anti-friction rollers surrounding the pin 10 to rotatably support the cutter thereon, the rollers having tapered end surfaces, washers spacing the ends of the cutter from the body, rings on the pin between the rollers and the washers, and annular lips on the rings cooperating with the end 15 surfaces of the rollers.

JOHN H. HOWARD.
ALFRED C. CATLAND.
